UNITED STATES PATENT OFFICE.

JACKSON CALVIN HAYNES, OF MOUNTPLEASANT, TENNESSEE, ASSIGNOR OF ONE-
THIRD TO C. H. BUTLER, JR., OF NASHVILLE, TENNESSEE, AND ONE-THIRD TO
A. A. SMITH, OF MOUNTPLEASANT, TENNESSEE.

FORE-TRUCK.

1,324,047.

Specification of Letters Patent.

Patented Dec. 9, 1919.

Application filed January 31, 1919. Serial No. 274,300.

To all whom it may concern:

Be it known that I, JACKSON C. HAYNES, a citizen of the United States, and a resident of Mountpleasant, county of Maury, 5 and State of Tennessee, have invented certain new and useful Improvements in Fore-Trucks, of which the following is a specification.

My invention relates to vehicle trucks and 10 more particularly to fore trucks used in connection with wheeled scrapers, and other animal drawn wheeled appliances, an object being to provide a simple, cheap and an efficient device whereby undue strain will be 15 taken from the draft animal's neck and shoulders, and also permit short turning on all conditions of land.

With this and other objects in view, my 20 invention consists in certain novel features of construction, arrangement and combination of parts as will be hereafter fully pointed out in the specification and claims, reference being had to the drawing forming a part hereof, in which,

25 Figure 1 is a top plan view of my improvements as applied;

Fig. 2 is a front elevation of same;

Fig. 3 is a top plan view showing the truck turning and the relative arrangement 30 of parts in that position;

Fig. 4 is a vertical section taken on line 4—4 of Fig. 1.

In carrying out my invention, the fore-truck comprises essentially a frame consisting of upper and lower cross beams 10 and 11 made of metal and intermediate beams 12 of less length than the top and bottom beams, and diagonally disposed braces 13 at each end which meet at about 35 midway between the upper and lower beams, leaving a space at each end in which the upright posts 14 of stub axles 15 are pivotally held between the ends of the upper and lower beams. The stub axles 15 have mounted to 40 rotate on them the wheels 16. Each stub axle has projecting rearwardly an arm 17, the rear ends of which are pivotally connected between the ends of a pair of links 18.

As shown the upper and lower beams 10 and 11 and the intermediate beams may be 45 made integral or they may be in separate pieces and rigidly connected together at the ends, but the several beams are to be so spaced from each other as to permit the in-

sertion between certain of them, of other 55 elements that form part of the complete unit. Thus, between the upper beam 10 and the upper intermediate beam 12 is mounted a wooden short reach 19, the front end of which is held between said beams by a bolt 20, which passes through all the beams at the center of the truck, the rear end of the short reach 19 is bolted to the upper end of a bent rearwardly extending brace 21 the forward end of said brace 21 being held to the lower beam by the bolt 20 before mentioned. An angular brace consisting of diagonally disposed rods 22 is bolted to the bottom beam 11 and at the apex of the angle to the rearwardly extending brace 21, 60 70 as plainly shown in the drawings.

Pivottally mounted between the intermediate beams 12 is the rear member 23 of a limber tongue and to the forward end of this member, the draft tongue 24, constituting 75 the remainder of the limber tongue, is pivotally mounted, as shown at 25 by a knuckle joint, so that the draft tongue may swing vertically above and below the plane of the rear member 23.

The member 23 of the limber tongue extending rearwardly has its rear end pivotally mounted between the pair of links 18, by a bolt 26, as shown in Fig. 4.

When the truck is used with a wheel 80 scraper, the hounds of the scraper are attached to the foretruck in the following manner: The bolt 27 which secures the rear end of short reach 19 to the bent brace 21 is sufficiently long to permit its use when 85 the cross beam 28 of the hound structure is connected to the end of the brace and said reach; the forward members 29 of the hounds converge and have extensions extending along the sides of the reach between the top beam and the upper intermediate beam 12, and are held in place by bolts 90 95 passed horizontally through said ends and through the short reach 19.

The intermediate beams 12 are maintained 100 spaced apart by connecting pieces or blocks 12^a which have their inner or opposed faces beveled as indicated at 12^b so that the tongue member 23 may be swung to its limit laterally and contact with an oblique surface 105 instead of striking a sharp corner and thus prevent breakage of the tongue.

When the draft team is swung to either

side, the tongue member 23 being pivoted at 20 swings between the intermediate beams to the corresponding side and the rear end of said tongue member 23 being pivotally secured 5 between the links 18 at their center cause the links to move longitudinally in the opposite direction to the turn, and as the ends of links 18 are pivotally connected to the rearwardly extending arms of the 10 stub axle, a turning leverage is exerted on said axles causing the wheels to swing close to the front and rear of the front beams of the truck, the beams constituting as a whole a bolster. By virtue of the particular mounting 15 and proportioning of the links 18, the tongue member 23 and the stub axle arms 17, a parallelogram is formed which will have right or oblique angles, accordingly as the truck is being drawn straight ahead or 20 swung to either the right or left.

The short wooden reach, the hounds, and the braces, which are rigidly connected together and which are coupled to the wheeled scraper are maintained against a 25 swinging motion either to the right or left at all times.

Should the draft animals go into a depression or the foretruck or scraper drop into a depression or strike an elevation, 30 the limber tongue by virtue of its jointed nature will remain in the same position with respect to the team, and thus no extra strain or pull will be put on the sides or shoulders of the animals. This is a very 35 important result of the peculiar construction and arrangement of the parts of this invention, as ordinarily in the use of wheeled scrapers, the pitching and twisting of the structures due to uneven condition 40 of the ground being worked causes dangerous and disabling sores, and hence curtails usefulness of the team.

I claim:

1. In an animal drawn foretruck, a trans- 45 verse frame or bolster comprising upper and lower beams, intermediate beams, the beams being vertically spaced apart, the intermediate beams terminating within the vertical plane of the ends of the upper and 50 lower beams, stub axles pivotally mounted between the spaced apart ends of the upper

and lower beams beyond the ends of the intermediate beams, lever arms projecting rearwardly from said stub axles, spaced apart links pivotally connected to the rear ends of said arms, a tongue section pivotally mounted intermediate its ends between the said intermediate beams, the forward end of said tongue section projecting in front of said beams, a draft tongue section 60 horizontally hinged to the front end of the first mentioned tongue section, and the rear end of the rear tongue section pivotally connected to the spaced apart links and between the same. 65

2. A foretruck as specified in claim 1, further characterized by a reach member secured to the frame and projecting rearwardly therefrom and a supporting brace secured to the lower beam of said frame 70 and pivotally to the rear end of said reach member.

3. A foretruck as specified in claim 2 and further characterized by lateral stays extending from the reach brace to the lower beam of the frame at each side of its vertical center and rigidly connected to said brace. 75

4. A foretruck as specified in claim 2 and further characterized by a hound construction the forward members of which are secured to the reach member adjacent to its connection with the frame, and its cross beam supported at the rear end of the reach member. 80

5. A foretruck comprising in combination a bolster having spaced apart upper and lower ends, stub axles pivotally mounted between said spaced apart ends, lever arms projecting rearwardly from said stub axles, a link member pivotally connected to the free ends of said lever arms, a tongue member pivotally mounted in said bolster, and pivotally connected at its rear ends to said link member at its center, and a short 90 reach member extending rearwardly from said bolster, means for supporting said reach member on said bolster, and brace means for supporting the rear end of said reach member. 95

JACKSON CALVIN HAYNES.
